Primary Examiner — Karen E Kearney*Assistant Examiner* — Michael Chong(74) *Attorney, Agent, or Firm* — MH2 Technology Law Group, LLP(57) **CLAIM**

The ornamental design for a connector sleeve with cutout, as shown and described.

DESCRIPTION

FIG. 1 is a front, top, left-side view of the connector sleeve with cutout;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof;

FIG. 7 is a bottom plan view thereof;

FIG. 8 is a top cross-sectional view along line VIII-VIII of FIG. 3;

FIG. 9 is a side cross-sectional view along line IX-IX of FIG. 3;

FIG. 10 is a rear cross-sectional view along line X-X of FIG. 4; and,

FIG. 11 is a front cross-sectional view along line XI-XI of FIG. 4.

The broken lines in the drawings depict portions of the connector sleeve with cutout that form no part of the claimed design.
